UNITED STATES PATENT OFFICE.

EDGAR D. TILLYER, OF SOUTHERBRIDGE, MASSACHUSETTS, ASSIGNOR TO AMERICAN OPTICAL COMPANY, OF SOUTHERBRIDGE, MASSACHUSETTS, A VOLUNTARY ASSOCIATION OF MASSACHUSETTS.

OPHTHALMIC LENS.

Application filed August 2, 1922. Serial No. 579,206.

To all whom it may concern:

Be it known that I, EDGAR D. TILLYER, a citizen of the United States, residing at Southbridge, in the county of Worcester 5 and State of Massachusetts, have invented certain new and useful Improvements in Ophthalmic Lenses, of which the following is a specification.

This invention relates to new and useful 10 improvements in the manufacture of ophthalmic lenses and more particularly to what is known in the art as a bifocal lens.

The main object of my invention resides in new and useful construction in the manufacture of lenses wherein the main body of the blank or distance portion of the lens is of one refractive index, while the button or reading portion is of a different refractive index and resides in novel means whereby 20 these two parts can be quickly and readily secured together to form a complete blank.

Another object of my invention is the provision of an ophthalmic lens wherein the main body blank as well as the button to be fitted thereto can be sold to the retail trade, it being understood that the buttons sold to the trade will be of various degrees with regard to the reading portion so that the retailer can readily fit up a bifocal lens 30 by using a body blank of the proper distance degree and attaching thereto a button of a proper reading portion to provide a complete lens.

A further object of my invention is the provision of a bifocal lens including a blank 35 having an opening cut there thru adapted to receive the button or reading portion which in turn is provided with a coating of very soft glass, Canadian balsam or any 40 other suitable type of adhesive, which is rendered invisible after being adhered to the parts. The button is fitted into position within the blank and the hole heated until the coating of the button has been 45 thoroughly fused with the blank.

A still further object of the invention is the provision of a bifocal lens wherein the two parts of the lens can be manufactured at a comparatively low cost and the parts 50 readily assembled by the retailer when desired.

With the above and other objects in view the invention consists in the novel features of construction, the combination and arrangement of parts hereinafter more fully

set forth, pointed out in the claims and shown in the accompanying drawings, in which—

Figure I is a front elevation of a lens blank constructed in accordance with my invention.

Figure II is a transverse sectional view of the blank.

Figure III is a side elevation of the button used in connection with the blank shown 65 in Figure I, and

Figure IV is a longitudinal section of the button illustrating the coating applied thereto.

In carrying out my invention I provide a 70 body blank 1 having formed therein an opening 2 and it will be understood that this opening 2 may be of any desired shape in accordance with the requirements of the trade. The body blank 1 is preferably provided with a finished surface 3 and with a semi-finished surface 4. While I have illustrated in the accompanying drawings a 75 plano lens it will be understood that the same invention may be carried out with other types of lenses.

If found desirable the opening 2 which is formed in the main blank 1 may be tapered or the opening cut straight thru with parallel walls as shown in Figure II. The 85 button 5 which is preferably of a different refractive index from the body blank is provided upon one end with a substantially curved surface 6, this curved surface 6 being adapted to project beyond the face of the 90 lens when the button is placed in position within the opening 2.

Particular attention is called to the fact that the button 5 is provided upon its exterior with a coating indicated at 7. This 95 coating 7 which is applied to the button is preferably of a very soft glass or may be of Canadian balsam if found practical or any other suitable or similar type of adhesive may be used.

After the button 5 has been placed within the opening 2 in the main blank of the lens, the two parts are heated to a fusing point, the adhesive applied to the outer surface of the button 5 being rendered invisible thru 105 the heat applied to the lens so that only the reading portion of the button 5 will be visible after the two parts of the lens have been adhered together.

These buttons 5 which I have shown as 110

formed separable from the blank 1 may be of various shapes if found desirable and are preferably to be constructed so as to readily fit within the opening 2 in the main blank 1. From this it will be apparent that a retailer may have any number of blanks 1 of various distant portions, on hand as well as various buttons so that when the case may require the proper button can be readily fitted to the proper distant portion of the lens and the two parts fused together and ground down to form a finished product.

It will be apparent from the above descriptions taken in connection with the illustrations in the drawings that I have provided a simple bifocal lens which will be inexpensive to manufacture but which at the same time will be completely effective in its use.

What I claim is:

1. A bifocal lens including a body blank having an opening therethrough, a button adapted to be inserted within said opening, and a coating of soft glass applied to the exterior surface of the button whereby the button will become securely fastened to the blank upon the application of heat to the soft glass.
2. The process of making a multifocal lens, comprising finishing one surface of a piece of glass to a lens surface, placing

an opening transversely through the surfaced glass, finishing one surface of another piece of glass to a lens surface, finishing the edges of the second piece of glass to the same peripheral contour as the opening in the first piece of glass, coating the peripheral edges of the second piece of glass with soft glass, placing the second piece within the opening of the first piece, heating the assembled pieces to fuse the soft glass to unite the two pieces, and finishing the sides opposite the surfaced sides of the united pieces to a finished lens surface to make a complete multifocal lens.

3. A multifocal lens, including a body blank having an opening transversely therethrough, a second blank inserted in said opening and a coating of soft glass between the two, fused by heat to secure the two together.

4. A multifocal lens including a body blank having an opening transversely therethrough, a second blank inserted in said opening, a coating of soft glass between the two, fused by heat, to secure the two together, a finished lens surface on each of the pieces on one side, the two surfaces merging in a line around the opening, and a single lens surface over the two pieces on the opposite side.

EDGAR D. TILLYER.
